PICKER SPINDLE MOUNTING FOR LOOMS

Application filed May 17, 1929. Serial No. 363,842.

This invention relates to improvements in picker spindles for looms and it is the general object of the invention to provide an improved mounting for the spindle which will relieve the latter of strains due to distortion of the lay.

In the usual loom the lay is moved back and forth by means of a pair of connectors which are located near the loomsides. The shuttle boxes extend beyond the loomsides and by reason of their momentum tend to continue moving when the connectors are momentarily at rest, with resultant twisting of the lay. In certain forms of looms it is desirable to 15 propel the shuttle by means of a picker which slides along a picker spindle. The inner end of the spindle is usually adjacent one of the connectors but is held fast with respect to the lay and is therefore placed 20 under a slight twisting strain twice for each pick of the loom, bending forwardly when the lay is on front center and bending backwardly when the lay is on back center. It is an important object of my present invention 25 to provide a pivotal connection between the spindle and the lay so placed that the spindle may move with the lay without being subjected to strains.

It is a further object of my present invention to provide a picker spindle mounting so 30 constructed that the outer end of the spindle may slide freely through a support, the inner end being held by the aforesaid pivotal construction.

35 It is found desirable from time to time to change the location of the picker spindle with respect to the box back or the center line of the shuttle and it is a still further object of my present invention to provide the pivotal 40 supports for the spindle with an eccentric feature which will permit the spindle to be adjusted within limited degrees relatively to the lay.

With these and other objects in view which 45 will appear as the description proceeds, my invention resides in the combination and arrangement of parts hereinafter described and set forth in the claims.

In the accompanying drawings, wherein 50 three forms of my invention are shown,

Fig. 1 is a rear elevation of one end of the lay having my invention applied thereto,

Fig. 2 is a top plan view taken in the direction of arrow 2, Fig. 1,

Fig. 3 is an enlarged rear elevation of a 55 part of Fig. 1, showing the preferred form of mounting,

Fig. 4 is a rear elevation similar to a portion of Fig. 1 but showing a modified form of mounting adaptable to old looms,

Fig. 5 is a top plan view taken in the direction of arrow 5, of Fig. 4, and

Fig. 6 shows a further modification which is adaptable to the forms shown either in 60 Figs. 1 or 4.

Referring particularly to Figs. 1 and 2 I have shown a lay 10 having a lay sword 11 and a lay end 12. The latter is provided with bearings 13 which are pivotally connected to the forward end of a driving rod or connector 14. The latter is connected to the top crank shaft not shown and operates to move the lay forwardly once for each pick of the loom.

The lay may be provided with box guides 15 and 16 located at the outer and inner ends respectively of the lay end, said guides determining the path along which a set of shifting shuttle boxes 17 move. The lay end is provided with a slot 18 through which extends a picker 19.

The picker is slidable along a picker spindle 20 the outer end of which extends through a barrel 21 supported by upper and lower screw eyes 22 and 23, respectively, said eyes being extended into the lay end as suggested in Fig. 2. In order to hold the barrel in position with respect to said screw eyes I provide upper and lower holding screws 24 and 25, respectively, which pass through the eyes and into the barrel. The latter is perforated so as to receive the outer end of the spindle 20.

The matter thus far described forms no part of my present invention, the lay and lay end being of usual construction and the parts associated with the barrel for supporting the outer end of the spindle being shown more particularly in co-pending application Ser. No. 332,692.

My present invention relates more particu- 100

larly to the means for mounting the inner end of the picker spindle which is seen at the left of Figs. 1 and 2. In the preferred form of my invention I provide the lay end with 5 upper and lower ears 30 and 31, respectively, which are spaced to receive a perforated eye 32 formed on the end of the spindle 20. This eye may be secured to the spindle proper in any approved manner as by welding or by 10 an upsetting operation. A pivot pin 33 extends through the ears and the eye and is held in position by means of cotter pins 34.

The pin 33 has a comparatively tight fit with both the ears and the eye of the spindle 15 so that the latter is held against appreciable relative movement with respect to the lay end. The fit, however, is sufficiently loose to permit the spindle to move around the axis of the pin as a pivot when the lay end moves 20 with respect to the lay as the latter reaches the extreme limit of either its forward or backward stroke. The outer end of the spindle moves freely through the barrel 21 so that said spindle is subjected to very little 25 if any strain due to distortion of any part of the lay.

The construction described in connection with Figs. 1 and 2 is usable on any loom, but on old looms which are not provided with 30 ears 30 and 31 but have formed as part of the lay end a bearing 40 I may employ the modification shown in Figs. 4 and 5 wherein a yoke 41 has a threaded extension 42 projecting into the bearing 40. A pin 43 extends through both parts of the yoke 41 and also the eye 32, said pin acting as a pivot for 35 the spindle. The object of the construction shown in Figs. 4 and 5 is to provide a substitute in old looms for the ears shown in the 40 preferred form.

In either of the forms already described I may modify the construction of the pivot pin so as to conform substantially to that shown at 50 in Fig. 6. Pin 50 may have an upper 45 enlarged cylindrical portion 51 and a lower smaller cylindrical portion 52 concentric therewith and provided on the lower end with threads 53. Intermediate the concentric portions may be located an eccentric 54 50 which is received by the eye of the spindle and lies between the upper and lower ears 30 and 31 when the pin 50 is applied to the preferred form of the invention. By means of a nut 55 which engages the lower end of 55 the stud 50 the latter may be held in any adjusted position, thereby permitting limited adjustment between the spindle and the lay. It is to be understood that the form of pin shown in Fig. 6 may also be applied to the 60 yoke 41 shown in Figs. 4 and 5 and it is not deemed necessary to illustrate this variation as the manner of its application will be readily understood.

It is believed from the description given 65 that the operation of the invention will be

clearly understood, the picker spindle being free to move around its pivotal pin and in this way being relieved of strains such as are common in the present forms of spindles.

From the foregoing it will be seen that I 70 have provided a form of spindle mounting which will permit the spindle to move freely with the lay and should the latter twist relatively to the lay, the distortion of the latter will take place without subjecting the spindle to any strains. It will further be seen that I have provided means for applying this feature of my invention to existing looms which are not provided with the ears 30 and 31. It will further be noted that by employing 75 the eccentric pin shown in Fig. 6 I may provide for a limited degree of adjustment between the picker spindle and the lay. It will also be noted that the picker spindle is pivoted about an axis substantially perpendicular to the direction in which the lay moves.

Having thus described my invention it will be seen that changes and modifications may be made therein by those skilled in the art 80 without departing from the spirit and scope of the invention and I do not wish to be limited to the details herein disclosed, but what I claim is:

1. In a loom having a lay movable back and forth in a given path and having a picker to move along the lay to propel a shuttle, a picker spindle along which the picker moves, and means to pivotally connect the lay and spindle, the axis of the pivot being substantially 95 perpendicular to the spindle.

2. In a loom having a lay movable back and forth in a given path and having a picker to move along the lay to propel a shuttle, a picker spindle along which the picker moves, and means to pivotally connect the lay and the spindle with an axis transverse of the path of movement of the lay.

3. In a loom having a lay movable back and forth in a given path and having a picker to move along the lay to propel a shuttle, a picker spindle along which the picker moves, and means to pivotally connect the lay and the inner end of the spindle, the axis of the pivotal connection being transverse of the 110 path of movement of the lay.

4. In a loom having a lay movable back and forth in a given path and having a picker to move along the lay to propel a shuttle, a picker spindle along which the picker moves, a pair of spaced bearing members, a pin extending through said members, and means to establish a pivotal connection between the pin and the spindle.

5. In a loom having a lay movable back and forth in a given path and having a picker to move along the lay to propel a shuttle, a picker spindle along which the picker moves, a pair of spaced bearing members, a pin extending through said members, and 125

means to establish a pivotal connection between the pin and the spindle, the axis of the pin being transverse of the path of movement of the lay.

5 6. In a loom having a lay movable back and forth in a given path and having a picker to move along the lay to propel a shuttle, a picker spindle along which the picker moves, a pair of spaced bearing members, a pin extending through said members, and means to establish a pivotal connection between the pin and the spindle, said members being removable from the lay.

15 7. In a loom having a lay movable back and forth in a given path and having a picker to move along the lay to propel a shuttle, a picker spindle along which the picker moves, a bearing member normally fixed to the lay but removable therefrom, and means defining a pivotal connection between the spindle and said member, the axis of said pivotal connection being substantially perpendicular to the length of the spindle, said member being rotatable relatively to the lay about an axis substantially parallel to the axis of the spindle.

20 8. In a loom having a lay movable back and forth in a given path and having a picker to move along the lay to propel a shuttle, a picker spindle along which the picker moves, a pivotal connection between the lay and the inner end of the spindle constructed to prevent longitudinal movement of the spindle away from the pivotal connection, and a sliding bearing for the outer end of the spindle.

25 9. A picker spindle for a loom lay, a pivotal support on the lay, said spindle having a straight body portion along which a picker may move and having a perforation in one end to cooperate with the pivotal support on the loom lay.

30 10. In a loom having a lay movable back and forth in a given path and having a picker to move along the lay to propel a shuttle, a picker spindle having one end held with respect to the lay and along which the picker moves, and means defining a pivotal connection between the other end of the spindle and lay to prevent the spindle from moving radially away from the axis of the connection, the spindle being movable about the connection when the lay bends during movement along the aforesaid path.

35 11. In a loom having a lay movable back and forth and subject to bending strains during movement thereof, a picker spindle along which the picker moves to propel the shuttle, a pair of supports on the lay, one for each end of the spindle, means defining a pivotal connection between one support and the corresponding end of the spindle effective to prevent relative longitudinal movement between the lay and said last named end of the spindle, the other support constructed to

have relative longitudinal movement relatively to the spindle when the lay bends.

In testimony whereof I have hereunto affixed my signature.

CARL J. LINDEGREN.
